Patented Oct. 5, 1920.

Wladimir Voina-Hansen,
INVENTOR

By *Frank C. Fischer*,
ATTORNEY

UNITED STATES PATENT OFFICE.

VLADIMIR VOINA-HANSEN, OF NEWARK, NEW JERSEY.

FILLER-COVER.

1,354,787.

Specification of Letters Patent.

Patented Oct. 5, 1920.

Application filed April 20, 1920. Serial No. 375,272.

To all whom it may concern:

Be it known that I, VLADIMIR VOINA-HANSEN, a citizen of the United States, residing in the city of Newark, county of Essex, and State of New Jersey, have invented certain new and useful Improvements in Filler-Covers, of which the following is a full, clear, and exact description, such as will enable others skilled in the art to which it pertains to make, construct, and use the same, reference being had to the accompanying drawings, and to numerals of reference marked thereon, forming a part of this specification.

15 My invention relates to covers for filler openings, and while I shall describe as a specific embodiment of my invention, a filler cover for automobile radiators, I do not intend to limit the invention to such use, as it will be apparent to those skilled in the art that my invention may be applied to tanks and any kind of container, generally.

The usual screw cap employed for automobile radiators usually becomes too hot to be handled with any degree of comfort, and is usually so tightly held that considerable exertion is necessary to loosen it. If it is left loose it is very likely to be lost. It often falls to the ground on account of it being too hot to be held, and thus accumulates dirt and other foreign matter in the exposed threads and therefore considerable time is required to replace the cap and the threads thereof often become damaged making the cap useless.

30 My invention has for its object to provide a filler-cover of simple, durable and efficient construction, in which the essential parts have been reduced to a minimum and which is readily operable to open or close and which will maintain a tight closure.

With these ends in view, my invention consists in certain novelties of construction and arrangements of parts as hereinafter set forth and pointed out in the claims.

45 While the preferred form of my invention is illustrated in the accompanying drawings, yet it is to be understood that minor changes may be made without departing from the scope thereof.

In the drawings,

Figure 1 represents, a side elevation of a filler-cover constructed in accordance with my invention mounted for use on an auto-

mobile radiator, part of which is represented in dotted lines.

Fig. 2 represents, a plan view of the same in its open position.

Fig. 3 represents, a side elevation in its open position with one of the side plates removed.

Fig. 4 represents, a similar view, in closed position, and

Fig. 5 represents, a central sectional view taken on line $x-x$ of Fig. 1 looking in the direction indicated by the arrows.

Similar numerals of reference refer to like parts throughout the specification and drawings.

In the drawings, 1 represents a casing 70 provided with a central bore or aperture 2 extending entirely therethrough, the lower portion of the casing terminating in an annular exteriorly screw-threaded portion 3, designed to have screw threaded engagement 75 with the screw-threaded portion of an automobile radiator opening, as clearly indicated in Fig. 1 of the drawings, and by means of which the device is secured thereto.

The shape of the casing 1, of the device, is 80 approximately square, although said shape may be of any other desired or convenient form.

Projecting outwardly from the front of the casing 1, preferably cast integral therewith, are two aligned apertured lugs 4-4 to receive the stem or shaft 5 of the handle 6.

Surrounding the shaft 5 between the interior faces of the lugs 4-4, to protect it from moisture, is a closely fitting tube 7, a 90 similar tube surrounding that portion of the shaft extending beyond the casing and located between the handle 6 and said casing.

Hingedly secured to the top of the rear portion of the casing, in any desired or convenient manner, preferably by means of a bifurcated lug 8 is a lid 9.

The under side of the lid is provided with an integral annular portion 10, circumferentially grooved to receive, preferably, a rubber gasket or ring 11 of circular cross section, designed to have seating engagement with a curved seat 12 arranged in the interior of the casing, surrounding the central bore or aperture 2 to form a tight 100 joint.

The opposite sides of the casing 1 are recessed, as clearly indicated in Figs. 2 and 3

of the drawings, sufficiently deep enough in order to operatively mount the gear wheels 13-13, designed to mesh with the pinions 14-14, which are made fast to the handle 6 5 in any desired or convenient manner.

The gear wheels 13 are revolubly secured in the recesses by means of the screws 15 10 passing central therethrough, the ends of said screws having screw threaded engagement with screw threaded apertures formed in the sides of the casing.

Each gear wheel 13 is provided with an outwardly extending lug 16, to which one 15 end of a connecting link 17, is secured in any desired or convenient manner, as for instance, by means of a screw 18, the other end of said connecting link being pivotally secured to one side of the lid, in any desired or convenient manner, as for instance, by 20 means of a stud 19 formed integral with the lid, a cotter pin passing through said lug to prevent accidental separation of the link from the lid.

One side of the lug 16 is provided with a 25 square portion 21 designed to engage with a shoulder 22 formed on the side of the casing as clearly indicated in Fig. 3 of the drawings, to limit the movement of the lid in an outward direction.

30 A pin or stud 23 is secured in said recess, as clearly indicated in Figs. 3 and 4 of the drawing, to be engaged by the rounded portion of the lug 16 to limit the movement of the gear wheel 13 when moved in the direction 35 of the arrow indicated in Fig. 4 of the drawings, after a tight joint has been made between the curved seat 12 and the rubber gasket 11. A cover plate 24 is secured to each side of the casing by means of screws 40 25 or the like.

It will thus be noted that rotation of the shaft 5 in one direction, to which the pinions 14 are secured and which are operatively connected with the gear wheels 13-13, will 45 open the lid 9, while rotation of the shaft 5 in the opposite direction will close the lid 9 causing the rubber gasket or ring 11 to have seating engagement with the curved seat 12 arranged in the top of the interior 50 of the casing, thereby forming a tight joint.

Experience has demonstrated that the organization above described is a highly efficient one, and while I have shown the preferred embodiment of my present invention, 55 I do not wish to be limited to the exact details of construction shown and described, as obvious modifications thereof, not involving the exercise of invention, may be made by any skilled mechanic, and such departures 60 from what is herein set forth, I consider within the scope and terms of my claims.

Having thus described my invention, what I desire to secure by Letters Patent is:-

1. In a device of the class described, a

casing having an opening therethrough, a 65 lid hingedly secured to said casing designed to have seating engagement with the top of the opening in said casing, means located within recesses formed in the sides of the casing and operatively connected with 70 means pivotally secured to said means and to the lid, and a handle operatively connected with the first named means for moving the said lid into and out of engagement with the opening in said casing. 75

2. In a device of the class described, a casing having an opening therethrough, a seat formed on the interior of said casing surrounding the said opening, a lid hingedly secured to said casing designed to have seating engagement with said seat, a rubber gasket carried by said lid, means located within recesses formed in the sides of the casing and operatively connected with means pivotally secured to said means and to the lid, 80 85 and a handle operatively connected with the first named means for moving the said gasket into and out of engagement with the seat in said casing.

3. In a device of the class described, a 90 casing having an opening therethrough and provided with recesses in its opposite sides, a seat formed on the interior of said casing surrounding the said opening, a lid hingedly secured to said casing, designed to have seating engagement with said seat, a rubber gasket carried by said lid, a handle rotatively secured to said casing, pinions rigidly secured to said handle, gear wheels rotatively secured in the recesses in the sides 95 100 of said casing operatively connected with the said pinions, and connecting links the ends of which are pivotally secured to said gears and to the sides of said lid.

4. In a device of the class described, a 105 casing having an opening therethrough and provided with recesses in its opposite sides, cover plates secured to said recessed sides, a seat formed on the interior of said casing surrounding the said opening, a lid hingedly 110 secured to said casing, designed to have seating engagement with said seat, a rubber gasket carried by said lid, a handle rotatively secured to said casing, pinions rigidly secured to said handle, gear wheels rotatively secured in the recesses in the sides of 115 120 said casing operatively connected with the said pinions, and connecting links, and means located in the recessed sides of said casing to be engaged by said gear wheels to limit the movement of said lid.

This specification signed and witnessed this 16th day of April, 1920.

VLADIMIR VOINA-HANSEN.
